Atty's.

UNITED STATES PATENT OFFICE

ATHERTON D. CONVERSE, OF WINCHENDON, MASSACHUSETTS

TOY DRUM

Application filed March 8, 1930. Serial No. 424,267.

My said invention relates to improvements in toy drums designed for children's use and aims to provide an improved drum of this character which can be manufactured at an 5 extremely low cost, both as to materials and workmanship, and further to provide a drum which will have the appearance and action of the customary drum and which will be strong and durable in use.

10 With said objects in view the invention includes the novel construction hereinafter described, the invention being defined by the claims appended hereto.

In order that the invention may be more 15 readily understood reference is made to the accompanying drawings in which—

Figure 1 is a side elevation of the drum with a part broken away to show it in section, and

20 Fig. 2 is an enlarged sectional detail through one of the corners,

Fig. 3 is a sectional view of the sheet metal cylinder at the commencement of the drum forming operation,

25 Fig. 4 is a view illustrating how the cylinder appears after the enlarged ends have been formed therein,

Fig. 5 is a view showing the next stage of 30 operation in forming the shoulder of re-entrant or channel shape, and

Fig. 6 is a view showing the head in position and how the parts appear prior to overturning the outer cylinder end.

Fig. 7 is a detail of one of the drum heads, 35 partly in section.

In proceeding to construct my novel drum I provide a cylinder of inflexible ductile material (metal) indicated at 1 in Fig. 3. By means of a suitable press I enlarge the ends 40 of this so as to provide end cylindrical portions 1a and annular outwardly facing shoulders 1b (Fig. 4). These shoulders serve to support and hold (as hereinafter described) the margins of the drum heads, and 45 for more secure retention I prefer to depress them to form annular channels, conveniently by pressing until the shoulder forming portions incline outwardly and downwardly as shown in Fig. 5.

50 Thereafter I supply a pair of disks 2 of

flexible material such as strong paper having upstanding peripheral flanges 2a and place these within the enlarged ends of the drum cylinder with the margins of the disk overlying the channeled shoulders and the peripheral flanges juxtaposed to the inner walls of the enlarged cylinder portions. I then place within the enlarged portions in juxtaposition to the inner faces of the peripheral flanges of the heads rings 3 of inflexible material such as stiff cardboard or paste board, whereafter by the use of a suitable press or die I roll or bend the outer edges of the cylindrical portions 1a over upon the outer edges of the rings as indicated at 1c which 55 forces them inward and causes their lower edges to clamp the margins of the heads against the channeled shoulders thereby 60 holding the heads in position. The forcing of the margins down into the channels places 65 the disks 2 under tension.

After the drum is complete the heads are covered with a moisture proof coating, and of course the cylinder or body may be painted or ornamented as desired.

The result is a drum which can be manufactured at an extremely low cost due to the few number of parts employed, the cheapness of material, and the economical manner of 70 assembly.

I claim:

1. A toy drum comprising a cylindrical body having enlarged integral end portions with outwardly facing annular channels at the inner ends of said enlarged portions, 75 disks of flexible material having their margins overlying said channels, rings within said enlarged ends and engaging said disk margins, and means for holding said rings with their inner edges pressed against the 80 disk margins to clamp them in said channels.

2. A toy drum comprising a cylindrical body having enlarged integral end portions with outwardly facing annular channels at the inner ends of said enlarged portions, 85 disks of flexible material having their margins overlying said channels, rings within said enlarged ends and engaging said disk margins, said enlarged portions having their 90 outer edges overturned upon the outer edges 95 100

of the rings and holding them with their inner edges clamping the disk margins in said channels.

3. A toy drum according to claim 1 in which the channels are formed by outwardly and downwardly inclined portions of the cylinder.

4. A toy drum comprising a cylinder of inflexible material having enlarged ends and 10 annular outwardly facing shoulders at the inner ends of said enlarged ends, heads of flexible material having marginal portions overlying said shoulders and peripheral cylindrical portions juxtaposed to the inner 15 walls of said enlarged portions, rings of inflexible material lying within said cylindrical portions of the heads, and means for clamping said rings in position.

5. A toy drum comprising a cylinder of 20 inflexible material having enlarged ends and annular outwardly facing shoulders at the inner ends of said enlarged ends, heads of flexible material having marginal portions overlying said shoulders and peripheral cy- 25 lindrical portions juxtaposed to the inner walls of said enlarged portions, rings of inflexible material lying within said cylindrical portions of the heads, said enlarged portions having their outer ends overturned upon 30 the outer faces of said rings.

In testimony whereof I affix my signature.
